UNITED STATES PATENT OFFICE.

GEORGE W. DIMMICK, OF BROOKLYN, NEW YORK, ASSIGNOR TO JAMES H. HART, (LIMITED,) OF SAME PLACE.

DESIGN FOR A SPOON, &c.

SPECIFICATION forming part of Design No. 20,801, dated June 2, 1891.

Application filed April 8, 1891. Serial No. 388,191. Term of patent 3½ years.

To all whom it may concern:

Be it known that I, GEORGE W. DIMMICK, a citizen of the United States, residing in the city of Brooklyn, in the county of Kings, in the State of New York, have invented and produced a new and original Design for Spoons and the Like, of which the following is a specification, reference being had to the accompanying illustrations, forming part thereof.

10 The figure shown in the accompanying photographic illustration represents a top plan view of a spoon in which my design is embodied.

15 The leading figure of the design consists in the representation within the cavity of the bowl *a* of the spoon of a view in perspective elevation of the Soldiers' Memorial Arch in the plaza of Prospect Park, in the city of Brooklyn, New York, such representation, 20 like that of the other figures upon the spoon and its handle, being produced by any of the well-known arts which are commonly employed in the decoration of articles which are composed of any of the precious metals, such 25 as etching, engraving, die-stamping, and the like. The handle *b* of the spoon, which consists of the shank *b'*, thumb-rest or clasping portion *b''*, and terminal portion or point *b'''*, may have upon the shank *b'* a suitably-prepared surface, upon which an appropriate 30 legend or any suitable ornamentation may be placed. Upon the thumb-rest *b''* of the

handle is a pictorial representation of the Lincoln statue in the Prospect Park plaza, in Brooklyn, the base and its superstructure 35 and the figure of Lincoln mounted thereon being represented in high relief upon the surrounding field. The terminal extremity or point *b'''* at the outer end of the handle may be a representation of the fountain in 40 the plaza of Prospect Park, Brooklyn, the larger and the smaller curved parts indicating, respectively, the outline of the lower and the upper series of jets, as seen when the fountain is playing. Below the base of the 45 fountain and bordering in its right and its left upper portion the field upon which the statue of Lincoln is produced may be any suitable floral or arboreal or other analogous ornamentation. 50

The invention having been thus described, what is claimed is—

The design for a spoon or the like herein shown and described, the same comprising the representation of the Soldiers' Memorial 55 Arch at the Prospect Park plaza within the bowl of the spoon and the representation of the Lincoln statue at the Prospect Park plaza upon the handle of the spoon, as set forth.

GEORGE W. DIMMICK.
